PAVING APPARATUS

Walter F. Benson, Great Falls, Mont.

Application May 19, 1958, Serial No. 736,362

12 Claims. (Cl. 25—118)

This invention relates to a paving apparatus, and more particularly to an apparatus of the so-called "do it yourself" type for building such concrete structures as patios and the like. The invention is an improvement over that disclosed and claimed in my copending application Serial No. 534,533, filed September 15, 1955, now Patent Number 2,843,912.

In the copending application referred to, there is disclosed an apparatus by which suitable slab-forming molds may be placed on a horizontal surface in predetermined relation to each other for the formation in the molds of slab elements. After these elements have set, the apparatus is removed and rearranged to provide elements, in combination with the previously formed slabs, forming molds for the pouring of additional slabs. This procedure is repeated until the entire pavement, patio, or the like has been completed. The apparatus is of such character that it readily may be employed by the average home owner in building patios and the like.

An important object of the present invention is to provide an improvement over the structure in my copending application by means of which the progressive work of forming successive slabs is greatly facilitated, the necessity for removing all of the structural elements after the formation of the initial slabs being eliminated.

A further object is to provide such an apparatus wherein any number of mold-forming units may be employed, each unit comprising a hub having novel means for anchoring it in position and for facilitating, without removal of certain of the hub members, the removal of the elements which form sides of the molds for making the initial set of slabs, and re-arranging the parts relative to those hubs which remain in position to provide for the formation of the next set of molds, thus facilitating and hastening the progress of the work in completing the pavement or patio.

A further object is to provide such an apparatus wherein each hub member is adapted to be accurately located with respect to the slab elements to be formed and to provide novel means for detachably connecting to the hub members the plates forming elements of the slab molds, such elements being detachable and movable to a different position and connected to a hub unit to facilitate the formation of the next slab.

A further object is to provide an apparatus of this character wherein the parts are assembled with respect to each hub member, whereupon holding elements in the form of spikes are driven into the ground to fix the hub member in position, and to provide each hub member with novel means whereby the mold-forming plates carried thereby merely may be swung upwardly to be disconnected from the hub members to be moved to a different position with respect thereto for continuing the paving operation in forming the next set of slabs.

A further object is to provide such an apparatus wherein the mold-forming plates connected to the hub members are detachably connected to the arms by which they are carried, thus providing great flexibility in the

2

formation of patterned patios through which any number of artistic designs may be formed.

A further object is to provide an apparatus of the general character discussed above wherein the hub members may be provided with a novel type depending flange to space them above the ground and to facilitate the use of reinforcing rods where heavier paving slabs are to be employed.

Other objects and advantages of the invention will become apparent during the course of the following description.

In the drawings I have shown two embodiments of the invention. In this showing:

Figure 1 is a fragmentary plan view illustrating the use of the apparatus in forming the initial paving slabs;

Figure 2 is a similar view showing the use of the apparatus in forming the next successive set of slabs;

Figure 3 is an enlarged perspective view of one of the hub members and associated elements;

Figure 4 is a fragmentary sectional view on line 4—4 of Figure 3;

Figure 5 is a fragmentary plan view showing the novel type of hinge connection between one of the hub members and the adjacent portion of one of the plate-supporting arms and associated elements;

Figure 6 is a fragmentary sectional view on line 6—6 of Figure 5;

Figure 7 is a fragmentary plan view of a completed slab showing the use of reinforcing rods;

Figure 8 is a detail section on line 8—8 of Figure 7;

Figure 9 is a plan view of a modified form of the invention showing its adaptation for use with reinforcing bars;

Figure 10 is an edge elevation of the same; and

Figure 11 is a detail sectional view on line 11—11 of Figure 10.

Referring to Figures 3, 4 and 5, the numeral 10 designates a hub member as a whole shown in the present instance as being octagonal. This is the preferred form in which the hub member is made, but it will become apparent that other shapes may be employed. As shown in Figure 3, the hub member 10 comprises a body 11 having eight vertical faces 12. Secured in any suitable manner to the top of the body 10 is a preferably integral plate 13 open in its center portion as at 14 and provided with radial projections 15 corresponding in number and arrangement to the faces 12 of the body 11. Each radial projection is formed at its radially outer edge with a half hinge 16 comprising spaced loops through which extends a hinge pin 17. The elements just described cooperate with other elements to support with respect to the hub a member for forming slab elements in a manner to be described.

Each body 11 is provided vertically therethrough with one or more openings 20 through which extend spikes 21 to be driven into the ground to position the hub members in forming the pavement or patio. Each spike 21 is provided at its upper end with an enlarged flat head 22 adapted to seat against the top of the body member 11 when the spikes are driven into the ground.

A plurality of mold plate supporting arms 25 are adapted to be connected to the hub members 10. Each such arm, as shown in Figures 3, 4 and 5, is provided at one end with a plate 26 secured to the arm by angle braces 27. Each plate 26 has one end overhanging what will be the radially inner end of each arm 25 when associated with one of the hub members 10, and such projecting end of each plate 26 is provided with a half hinge 28 comprising spaced fingers adapted to register with the spaces between the loops of the half hinge 16. The fingers 28 are approximately semicircular in cross section as shown in Figure 6, having their ends 29 terminating

in the horizontal position of the arm 25 approximately above the center of the circle forming the fingers 28. This arrangement facilitates the connection of the half hinge members 16 and 28 to each other and the disconnection of such elements after the completion of certain slab elements as described below.

A mold plate 32 is secured to the outer end of each arm 25 by angles 33. These elements are bolted together as at 34 whereby the plates 32 are removable and interchangeable according to the desired design of the pavement or patio. Preferably, each plate 32 is arranged at an angle to the vertical as clearly shown in Figure 4.

In the use of the apparatus, the units described above are set up initially substantially as shown in Figure 1 so that combinations of the plates 32 cooperate with each other to form molds for the pouring of initial slabs A. Certain others of the plates 32, at the margin of the walk or patio, cooperate with an edge form 35 to form slabs B shown in the present instance as being identical with the slabs A. In the use of the apparatus as illustrated, each side of each of the slabs A and B is equal in length to the diagonal distance between adjacent corners of adjacent slabs, in which case the same mold plates 32 will be used to form subsequent slabs C as illustrated in Figure 2. In the final use of the apparatus as illustrated, slabs D are formed (Figure 7).

In Figures 9, 10 and 11, there is illustrated a modified form of the invention which adapts it for use for installing reinforcing bars where heavier pavements or patios are desired. Most of the parts employed in the modified form of the invention are identical with those previously described and have been indicated by the same reference numerals. In the modified form of the invention, the body 11 is provided therewith beneath with a depending height block 40, having a flat bottom surface adapted to rest on the leveled surface of the ground. Such height block may be reduced in size relative to the body 11 to provide for the arrangement adjacent thereto of reinforcing bars 41. The use of the height block, of course, increases the thickness of the resultant slab, and to this end, the mold plates 32 are provided with depending flange portions 42, preferably inclined from the vertical to a greater extent than the plates 32, and provided with slots 43 arranged at such a distance apart as to accommodate the reinforcing rods 41 lying adjacent the sides of the height block 40.

Operation

The area to be paved is leveled and otherwise prepared in the usual manner, and forms 35 are placed on the desired number of sides of such area. Assuming that the left-hand slabs or blocks A and B in Figure 1 represent the extreme left-hand end of the area to be paved, it will be understood, of course, that one of the forms 35 will extend downwardly along the left-hand edges of such blocks. In such case, the arm 25 of the hub member lying between such blocks will be eliminated. Otherwise, such hub will be connected as shown to the two left-hand blocks, to the block A to the right of the hub member referred to, and to the corresponding block A to the left of such hub member. The positions of each pair of the block members B will be measured to locate adjacent parallel edges thereof at the proper distance from each other. This is done by employing arms 25 of such length that the distance between the remote faces of each pair of plates 32 having their upper ends in engagement with the form 35 will be equal to twice the distance from the center of the intervening hub member 10 to the remote face of the plate 32 adapted to form the nearest side of the intermediate slab A. In the embodiment shown, the lengths of the plates 32 will be such that the diagonal distance between each upper corner of the slab A as viewed in Figure 1 to the nearest corner of the closest slab B will be equal to the length of one of the plates 32. This is a highly practicable arrange-

ment since, as pointed out below, the same plates 32, employed for forming sides of the slabs A and B, also can be employed for forming sides of the slabs to be arranged in the spaces initially occupied by the two hub members 10 adjacent the form 35.

Assuming that the left-hand upper hub member 10 and associated elements as viewed in Figure 1 have been so placed, successive hub members 10 and associated parts along the form 35 are similarly spaced so that oppositely facing plates 32 of successive units will define blocks B which will be of a width between the oppositely facing plates 32 referred to, equal to the length of each of the plates 32. With such arrangement, square blocks B will be formed, although it will become apparent that the present apparatus is not limited to the formation of the particular design shown or to the specific shapes of the elements of the slab.

Having placed hub members 10 and associated elements along the length of the form 35 in the manner described, the next lower line of hub members 10 and associated elements will be placed as shown in Figure 1. This procedure may be repeated for any distance longitudinally along the form 35 and for any distance transversely of form 35, depending on how many hub members 10 and associated elements are available. The entire area of the patio or the like is covered with the present apparatus in the manner described, or a part of the desired area at a time will be covered and the formation of the blocks A and B carried out in successive steps.

The hub members 10 are positioned in the manner referred to with the spikes 21 removed, and when each hub member has been accurately placed in position, the spikes will be driven into the ground, thus anchoring the elements in proper position. As pointed out, the surface to be paved is leveled and smoother prior to using the present apparatus. Since the plates 32 are of equal widths vertically thereof and are arranged with their edges in contact with the smooth surface, it will be apparent that the upper edges of the plates 32 will all lie in a common plane. Having so placed the units, the slabs A and B will be poured and leveled off in the plane of the upper edges of the plates 32.

After the slabs A and B have set or hardened, steps are taken to provide for the pouring of the next successive slabs. As previously stated, the plates 32 are inclined from the vertical as shown in Figure 4. After the initially formed slabs have been set, therefore, the operator may swing the arms 25 upwardly to move the plates 32 out of molding position. In the case of the hub members 10 and associated elements arranged adjacent the form 35, complete removal of the units takes place to open the spaces for the pouring of the next slabs. In the case of the second row of hub members 10, a different operation is performed. These hub members are left in position, and the plates 32 and the adjacent ends of the arms 25 are swung upwardly. With the arms 25 arranged at an angle of 45° or more to the horizontal, the hinge fingers 28 may be released from the pin 17 and removed from their positions. The hinge fingers 28 are then placed in position with respect to those half hinges 16 which are arranged at 45° between the half hinges previously employed. Supporting the arms 25 at an angle of at least 45° to the horizontal, the hinge fingers 28 are now arranged between the loops of the half hinges 16 referred to and engaged around the corresponding pins 17. The arms 25 and associated plates 32 are then dropped into position as shown in Figure 2, in engagement with the prepared sub-surface. The spaces between adjacent pairs of slabs B and the next adjacent row of slabs A will now be enclosed as shown in Figure 2 for the pouring of the slabs C. These areas, of course, will be bounded by the form 35, adjacent edges of the slabs B and the intermediate slabs A, and by two of the plates 32.

In the case of the third row of hubs 10 and associated elements, complete removal of such elements is performed

as in the case of those arranged between the blocks B. This will leave a row of hexagonal spaces to be filled in to form what will be slabs D in Figure 2. In other words, assuming that an indefinite number of rows of hubs 10 and associated elements are employed, the odd-numbered rows will be completely removed and the even-numbered rows will be left in position with the arms 25 of each retained molding unit arranged at 45° to the vertical and horizontal as shown in Figure 2. Two plates 32 of each molding unit as viewed in Figure 2 will form sides of slabs C, while the other two plates 32 of downwardly diverging arms 25 will form sides of the slabs D.

With the parts so re-arranged, the enclosed areas for the slabs C and D will be poured and leveled to the common planes of the slabs A and B, the form 35 and the upper edges of the plates 32. After the slabs C and D have set or hardened, all of the remaining hub members 10 and associated elements will be completely removed in the manner described by swinging upwardly on the arms 25 and then lifting the molding units from the ground. Where each such unit is removed, there will be left an octagonal space. Each uppermost such space, as viewed in Figure 2, will be surrounded by edges of blocks A, B, C and D, while successive rows of such spaces will be bounded by adjacent edges of blocks A and D. Concrete is then poured into all such spaces to form blocks E. The pouring and leveling of the blocks E completes the formation of the pavement or patio, and it will be apparent that the operation may be carried out progressively and easily with a minimum degree of skill.

Where deeper reinforced slabs are desired, the form of the apparatus shown in Figures 9, 10 and 11 is employed. The reinforcing rods 41 are placed so as to extend on opposite sides of the height block 40 of each unit 10 with the reinforcing rods projecting through the grooves 43. The modified form of apparatus is so designed that a thicker slab will be formed and the depending flanges 42 of the plates 32 will support such plates with their upper edges in the proper plane to form successive slabs. As previously stated, the flanges 42 are inclined from the vertical to a greater degree than the plates 32, and this is to facilitate the upward swinging of the arms 25 when the plates 32 are to be removed from position. With either form of the invention, the resulting patio will appear as shown in solid lines in Figure 7. Where the modified form of the invention is used, the pattern of the reinforcing rods 41 will be as shown in dotted lines in Figure 7. The height block 40 being substantially smaller in horizontal dimensions than the lengths of the plates 32, it will be apparent that the reinforcing bars 41 will lie within the areas of all of the slab elements formed, including the smaller blocks A and B, thus providing adequate reinforcement for the resultant pavement or patio.

The invention has been described in accordance with the illustration of the parts in the drawings, but it will be apparent that a wide variety of designs may be achieved, presenting a high degree of artistic or esthetic appeal. For example, the plates 32 (Figure 1) may be arcuately formed as sections of circles having their centers at the centers of the respective hub members 10. In this case, when such plates 32 are employed, the slabs E will be circular. It is contemplated, in order to reduce the expense involved in constructing pavements or patios by home owners, that units of the present invention be stocked by hardware and building supply dealers for rental to home owners. Thus, without the expense of purchasing the apparatus, the home owner may rent the apparatus and construct his own pavement or patio. As previously stated, the invention may be used with great facility and without substantial skill thus permitting the constructing of the pavement or patio at a relatively low cost.

It will be apparent that in the apparatus as illustrated, each hub 10, together with its associated height block in

the modified form of the invention, is formed as an equiangular polygon. This will be the shape most commonly used.

In a little different aspect, the invention comprises a plurality of mold frames open vertically therethrough and adapted to rest on a horizontal surface to constitute concrete forms. For example, the mold frame for the upper central slab B is formed by the board 35 and the three surrounding hubs 10 and associated elements, and such frame constitutes wall portions certain of which, namely the elements 32 of the molding units, constitute plates associated with certain of the hub portions. Each of the molding frames for the slabs A (except for those at the right and left hand extremities of the platform which will be formed by mold boards) will be formed by four surrounding plates 32 carried by the arms 25 of each of the four surrounding hub members 10. Therefore there is a definite cooperative relationship between the different hub members and associated elements which cooperate to 20 form slabs in the initial practice of the invention.

The constructions as shown embody the invention in preferred forms, but it is intended that the disclosure be illustrative rather than definitive, the invention being defined in the claims.

25 I claim:

1. For use in laying concrete platforms and the like on a horizontal surface, a molding unit comprising a polygonal horizontal body adapted to rest on said surface, an arm projecting from one side of said body, a molding plate carried by the end of said arm remote from said body, said body and said plate being of the same height, whereby, when they rest on a flat surface, the tops thereof lie in a common plane, said side of said body and the adjacent end of said arm being provided with coacting 30 detachable connecting elements, such elements being identical at each side of said body whereby, when said unit is in a predetermined place and said plate has been used in the formation of a concrete element at the side thereof remote from said body, said arm may be disconnected 35 from one side of said body and moved and connected to another side thereof for re-use of said plate in a molding operation without moving said body.

2. For use in laying concrete platforms and the like on a horizontal surface, a molding unit comprising a 45 polygonal horizontal body adapted to rest on said surface, an arm projecting from one side of said body, a molding plate carried by the end of said arm remote from said body, said body and said plate being of the same height, whereby, when they rest on a flat surface, the tops thereof 50 lie in a common plane, said side of said body and the adjacent end of said arm being provided with coacting detachable connecting elements, such elements being identical at each side of said body whereby, when said unit is in a predetermined place and said plate has been used 55 in the formation of a concrete element at the side thereof remote from said body, said arm may be disconnected from one side of said body and moved and connected to another side thereof for re-use of said plate in a molding operation without moving said body, and anchoring 60 means passing through said body and through and below said horizontal surface to anchor said body in a predetermined position.

3. For use in laying concrete platforms and the like on a horizontal surface, a molding unit comprising a 65 polygonal horizontal body adapted to rest on said surface, and arm projecting from one side of said body, and a molding plate carried by the end of said arm remote from said body, said body and said plate being of the same height, whereby, when they rest on a flat surface, the tops thereof lie in a common plane, each side of said body being provided with identical spaced loops 70 having a pin projecting therethrough, the end of said arm adjacent said body being provided with detachable elements engageable in the spaces between said loops and around said pin, said detachable elements curving

around said pin and being open at the side thereof toward said arm whereby, upon the upward tilting of the end of such arm remote from said body, said detachable elements may be disconnected from said pin and engaged between said loops and the pin associated therewith at another side of said body without moving said body.

4. For use in laying concrete platforms and the like on a horizontal surface, a molding unit comprising a polygonal horizontal body adapted to rest on said surface, an arm projecting from one side of said body, a molding plate carried by the end of said arm remote from said body, said body and said plate being of the same height, whereby, when they rest on a flat surface, the tops thereof lie in a common plane, each side of said body being provided with identical spaced loops having a pin projecting therethrough, the end of said arm adjacent said body being provided with detachable elements engageable in the spaces between said loops and around said pin, said detachable elements curving around said pin and being open at the side thereof toward said arm whereby, upon the upward tilting of the end of such arm remote from said body, said detachable elements may be disconnected from said pin and engaged between said loops and the pin associated therewith at another side of said body without moving said body, said body being provided with anchoring elements projecting from the bottom thereof to be inserted through and below said surface to anchor said body in a predetermined position.

5. For use in laying concrete platforms and the like on a horizontal surface, a molding unit comprising a polygonal horizontal body adapted to rest on said surface, an arm projecting from one side of said body, a molding plate carried by the end of said arm remote from said body, said body and said plate being of the same height, whereby, when they rest on a flat surface, the tops thereof lie in a common plane, each side of said body being provided with identical spaced loops having a pin projecting therethrough, the end of said arm adjacent said body being provided with detachable elements engageable in the spaces between said loops and around said pin, said detachable elements curving around said pin and being open at the side thereof toward said arm whereby, upon the upward tilting of the end of such arm remote from said body, said detachable elements may be disconnected from said pin and engaged between said loops and the pin associated therewith at another side of said body without moving said body, said body having vertical openings therethrough at spaced points, and a spike insertable through each of said openings and through and below said surface to anchor said body in any predetermined position.

6. For use in constructing concrete platforms and the like on a horizontal surface, a molding unit comprising a horizontal angular polygonal body, a height block projecting downwardly beneath said body concentric therewith and smaller than said body and having its sides parallel to the respective sides of said body, said height block having its bottom lying in a horizontal plane and adapted to rest on said surface, an arm projecting from one side of said body and a molding plate carried by the end of said arm remote from said body, said plate having horizontal top and bottom edges the latter of which is adapted to rest on said surface, the upper edge of said plate lying in a common horizontal plane with the top of said body, said sides of said body and the adjacent end of said arm being provided with coacting detachable connecting elements, such elements at each side of said body being identical whereby, when said unit is in a predetermined place and said plate has been used in the formation of a concrete element at the side thereof remote from said body, said arm may be disconnected from said one side of said body and moved and con-

nected to another side thereof for the re-use of said plate in a molding operation without moving said body, said plate in the bottom thereof having slots spaced apart a distance greater than the distance between opposite sides of said height block for the insertion of reinforcing rods in such slots and along such sides of said height block.

7. Apparatus according to claim 6 wherein said detachable connecting elements at each side of said body comprise spaced loops forming half hinges and a hinge pin projecting through said loops, the elements connected to said adjacent end of said arm comprising substantially semicylindrical loops insertable in the spaces between said loops whereby said semicylindrical loops are detachable from the pin at one side of said body and insertable between the loops and engageable with the pin at another side of said body.

8. Apparatus according to claim 6 wherein said body is provided with vertical elongated anchoring elements spaced apart such a distance that they lie wholly within the area of said height block, said anchoring elements being insertable through and below said surface to fix said body in any predetermined position.

9. Apparatus according to claim 6 wherein said body is provided with vertical parallel openings therethrough lying wholly within the area of said height block, and elongated pointed anchoring elements passing through said openings and through and below said surface to anchor said body in any predetermined position.

10. Apparatus for use in constructing concrete platforms on a flat surface, comprising a plurality of frames open vertically therethrough and having narrow substantially vertical wall portions cooperating with the flat surface to form concrete forms, certain of said wall portions constituting horizontally elongated mold plates and said frames being spaced from each other, a plurality of hubs, an arm connected at one end to each of certain of said plates, each hub being horizontal and polygonal and having at each side thereof identical connecting means, the other end of each arm having means coacting with and operative for detachably connecting such arm with one of said connecting means, adjacent corners of two of said frames and the two slabs formed therein being spaced from each other whereby, after said frames have been filled with concrete to form slabs and such concrete has set, one of said arms may be disconnected from its associated hub and said coacting means moved to a different side of said associated hub whereby the associated plate will span the distance between said corners of said two slabs to cooperate with the edges of such slabs in forming a mold for the formation of another slab.

11. Apparatus according to claim 10 wherein each hub is provided with anchoring means projecting through and below said flat surface to anchor each hub in predetermined relationship to the other hubs.

12. Apparatus according to claim 10 wherein each hub forms an equi-angular polygon and is provided therebeneath with a correspondingly shaped polygonal height block adapted to rest on said surface and having each side thereof arranged inwardly of and parallel to one side of said hub, each mold plate being of a vertical height equal to the combined height of each hub and its associated height block, with the tops of said hubs and the top edges of said plates lying in a common plane, each plate being provided in the bottom edge thereof with a pair of slots spaced apart a distance slightly greater than the distance between opposite sides of certain of said height blocks for the extension of reinforcing rods through said slots and along such sides of said height blocks.
